UNITED STATES PATENT OFFICE

2,487,366

SANDBLAST GUN

Glenn J. Penno, Longmont, Colo., assignor to
 Tornado Manufacturing Company, Inc., Denver, Colo., a corporation of Colorado

Application October 13, 1947, Serial No. 779,433

1 Claim. (Cl. 51—8)

1

This invention relates to a gun for spraying fluids or blasting with abrasives, and has for its principal object the provision of a simple and highly efficient device which can be used for cleaning and preparing surfaces by means of an abrasive blast, and which will, when desired, prevent loss of the abrasive used in the blast.

Another object of the invention is to so construct the device that it may be quickly and easily converted into a spray gun for spraying surface coating compositions such as paints, enamels, etc.

A further object of the invention is to so construct the device that the portions which are subjected to rapid wear due to the abrasive action of the material, can be quickly and easily removed and replaced without disassembling or interfering with the construction of the gun, per se, and in which the operative relation between the air stream and the solid or liquid material will be automatically adjusted when the device is changed over for different uses.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a side view of the improved abrasive gun, illustrating it arranged for gathering and returning the used abrasive;

Fig. 2 is a front view thereof;

Fig. 3 is a detail view illustrating an air jet nozzle employed in the improved gun;

Figs. 4 and 5 are detail views of alternate forms of nozzle tubes which may be used with the improved gun;

Fig. 6 is a detail view of a nozzle tube retaining disc which is used in the gun;

Fig. 7 is a vertical, longitudinal section, taken on the line 7—7, Fig. 2; and

Fig. 8 is a fragmentary enlargement of the mid-portion of Fig. 7.

The abrasive gun comprises a solid metallic body portion 10 formed with a pistol-like hand grip 11 and provided with a hanging hook 12. A supporting boss 13 extends downwardly from the body portion 10, terminating in a threaded nipple 14. A nut 15 threaded on the nipple 14 acts to clamp a container cap 16 against the

2

boss 13. A container 17 is threaded into the cap 16 so as to be supported on the boss 13.

The handle 11 is drilled with an air passage 18, the extremity of which is threaded to receive a hose nipple 19 to which an air supply hose 20 is connected. A cross air passage 21 is drilled into the butt of the body portion 10 and closed by means of a suitable plug 22. The cross passage 21 communicates between the air passage 18 and a valve chamber 23.

The valve chamber 23 is threaded to receive a valve housing 24 through which a valve stem 25 projects. The valve stem carries a valve member 26 against a head 27 formed on the stem 25. The stem is provided with a packing ring 28 which seals the stem 25 to the housing 24.

The housing is provided with air ports 29, through which air passing beneath the valve 26 may discharge. When the housing 24 is in place in the valve chamber 23, the ports 29 align with an air discharge passage 30 extending through the muzzle of the body portion 10.

The valve 26 is lifted from its seat by means of a trigger 31 hingedly mounted in a trigger 32 cavity in the body portion 10 upon a trigger pin 32. The trigger acts as a cam and bears against a head member 33 threaded on the lower extremity of the valve stem 25.

The discharge passage 30 is counter-bored for the major portion of its length to a larger diameter to provide a shoulder 35. The counter-bored portion is designed to receive a plurality of interchangeable nozzle tubes. In Fig. 3 a nozzle tube 36 is illustrated which fits snugly into the counter-bored portion of the discharge passage 30 and is locked in place therein by means of a U-shaped locking disc 37 which fits into an indented groove 38 in the nozzle tube 36.

The disc 37 is clamped against the forward extremity of the threaded nipple 39 by means of a clamping bushing 40 so that the nozzle tube is accurately located in a pre-determined position in the counter-bore of the air passage 30.

The inner extremity of the nozzle tube 36 carries a nozzle jet 41 which is illustrated more in detail in Fig. 3. The material to be sprayed enters the nozzle tube 36 through a feed port 42 formed in the lower wall thereof and opening to a feed passage 43.

The jet 41 is designed specifically for a certain fluid or material to be used in the gun. The nozzle tube 36 is similarly designed, and the size of the opening 42 and its position from the end of the tube are determined by the particular material or fluid with which it is to be used.

Thus, to change the gun for different materials, it is only necessary to withdraw the nozzle tube and its jet and replace them with the proper nozzle tube and jet. Each jet is provided with a Venturi passage 44 for forming the air jet, and with a reduced extremity 45 which fits snugly into the end of the tube 38.

The material being projected by the gun is raised from the container 17 through a riser tube 46 which extends downwardly and forwardly to a point adjacent the bottom of the container. The suction created by the air stream flowing into the tube 36 draws the material upwardly in the riser tube 13 and feed passage 43.

For spraying liquids, such as cleaning solutions, etc., a nozzle tube such as illustrated in Fig. 4 is employed. For sand blasting and the like, a nozzle tube such as illustrated in Fig. 5 may be used, which is provided with a protecting shield 47 threaded on the extremity of the tube for preventing sand and abrasive particles from being thrown back against the operator's hand.

If the gun is used with abrasive material which it is desired to retain, a flexible hood 48 may be threaded onto the forward extremity of the nozzle tube 36. The hood has a flaring, funnel-like shape, and is preferably made of flexible material such as canvas, rubber, or the like, so that it may be pressed directly against the surface being blasted.

The sides of the hood 48 are provided with discharge screens 49 through which the air may escape. The hood is also provided with a receiving hopper 50 which is connected to a return tube 51 by means of a suitable union 52. The return tube 51 extends through, and is supported by, the container 11. The sand or other abrasive, after striking the surface to be cleaned, falls into the hopper 50 and is drawn therefrom back to the container 17 by the vacuum in the latter, assisted by the pressure in the hood 48.

While a specific form of the improvement has

been described and illustrated herein, it is desired to be understood that the same may be varied, within the scope of the appended claim, without departing from the spirit of the invention.

Having thus described the invention, what is claimed and desired secured by Letters Patent is:

A gun for spraying fluids and blasting with abrasives, comprising: a substantially horizontal body portion; means for supplying air under control into the rearward extremity of said body portion; an air passage in said body portion; a nozzle tube bore extending into the forward extremity of said body portion in alignment with and communicating with said air passage, said bore being of larger diameter than said air passage; a feed passage opening through the bottom of said bore; means for supplying material to said feed passage; an air jet member positioned in the rearward extremity of said bore between said feed passage and said air passage; a nozzle tube positioned in the forward extremity of said bore and fitted to said air jet at its rearward extremity, said nozzle tube having an opening in its bottom wall communicating with said feed passage; a peripheral receiving groove in said nozzle tube forwardly of said body portion; a U-shaped locking disc fitted into said groove; and means for clamping said disc to said body portion to lock said nozzle tube in place.
